(57) CLAIM

The ornamental design for a weight, as shown and described.

DESCRIPTION

FIG. 1 is a perspective front view of the weight showing my new design;

FIG. 2 is a perspective back view thereof;

FIG. 3 is a front view thereof;

FIG. 4 is a side view thereof;

FIG. 5 is a bottom view thereof; and,

FIG. 6 is a perspective view thereof with dashed lines shown in a condition of use with multiple weights.

The broken lines in FIG. 6 are included for purposes of illustrating portions of the pen that form no part of the claimed design.

1 Claim, 6 Drawing Sheets
